UNITED STATES PATENT OFFICE.

CHARLES W. DONHOLT, OF RIDGEWOOD, NEW JERSEY.

PACKAGE-TIE.

1,164,270.

Specification of Letters Patent. Patented Dec. 14, 1915.

Application filed May 8, 1914. Serial No. 337,099.

To all whom it may concern:

Be it known that I, CHARLES W. DONHOLT, a citizen of the United States, and a resident of Ridgewood, in the county of Bergen 5 and State of New Jersey, have invented certain new and useful Improvements in Package-Ties, of which the following is a specification.

This invention relates to package-ties for 10 connecting and tensioning the ends of tie-cords for packages of various kinds, and the main object of the invention is to provide a simple, cheap and effective device of this class which can be quickly attached to and 15 detached from the tie-cord and package and maintain a firm grip on said cord without necessitating the use of a knotted cord and without injuring the cord used.

Other features of the invention not hereinbefore referred to will be hereinafter described and claimed and are illustrated in the accompanying drawing in which—

Figure 1 is an illustrative view of a package having applied thereto a package-tie constructed in accordance with the present invention and connecting the ends of the package tie-cord; Fig. 2 is an enlarged edge elevation of the same looking from one side of the device, and Fig. 3 is an end elevation 30 of the device on an enlarged scale.

In carrying the invention into effect the tie-piece or package-tie proper may be made with a body portion of any suitable kind carrying one or more cord-clamps properly 35 constructed as hereafter described. Usually, however, the whole tie-piece will be made from sheet material, preferably spring metal. The body portion is approximately diamond-shaped as viewed in plan, but bent 40 or curved so as to be substantially concavo-convex, as viewed in edge elevation in Fig. 2. This curved body portion of the tie-piece is designated by 2. At one or both ends thereof it has a suitable cord-clamp or cord- 45 clamps for gripping a considerable portion of the length of the cord. In the preferred construction shown there are two of these cord-clamps one at each end of the tie-piece and, facing inwardly, but preferably the 50 extreme inner edges of the clamps are disposed at a considerable distance apart, as will be seen in Fig. 1, in order to facilitate the placing of the cord in position in one cord-clamp when the device is engaged and 55 the thumb of the user substantially covers the other cord clamp.

The two cord-clamps of the tie-piece are usually formed in part from the end portions of the body 2 and in part from bent-up elements or jaws formed by bending on the 60 lines 3 and 4 which here define the ends of said body portion 2. The lines 3 and 4 also constitute the meeting lines of the jaws of the respective cord-clamps formed by bending up the elements just mentioned. These 65 bent-up portions are indicated at 5 and 6, and constitute the upper jaws of the cord-clamps, *c* and *c'*.

The package tie is preferably relatively wide to provide relatively wide cord-clamps, 70 and has a slot of considerable length for receiving and gripping the cord to be tied around the package. In the construction illustrated this slot, which is designated by 75 7, extends approximately half the width of the cord-clamp (measured in the direction of the width of the tie-piece) leaving the upper and lower jaws of each cord-clamp directly connected with each other for about half the width of each cord-clamp. The 80 portion of each cord-clamp which is not cut in the meeting line of its jaws is a spring-clamp of relatively great width in the construction shown and adapted to exert pressure throughout its width upon the 85 cord at all points in the length of such cord-clamp (measured in the direction of the length of the tie-piece) after the cord enters the jaws of the clamp sufficiently to be in clamping relation therewith. Thereafter the clamping pressure upon the cord 90 as it approaches the meeting line of the jaws increases because the pass between the jaws tapers or decreases in width from the entrance of each pass to the jaws. Thus in 95 the preferred construction a gradually increasing pressure is exerted as the section, 8, for example, of the cord, *C*, is forced home, that is, in contact with the back wall of the cord-clamp *c*, at the meeting line 3 of the 100 jaws of said cord-clamp.

The clamping of the cord between the portions of the cord clamp jaws separated by the slot 7, for example, is different from the clamping action between the directly 105 connected parts of the jaws just described. The spring-metal jaws being entirely separated in this zone by the slot 7 are more flexible than the portion of the clamp not slit, and the slot 7 is usually considerably 110 narrower than either of the passes 9 and 9'. Because of this the cord *C* is gripped

strongly by the separated jaws at opposite sides of the slot 7, and particularly as it approaches the end wall of said slot, by converging walls tapering toward the back wall 5 of the slot. Thus, when the end of the cord is passed into the cord-clamp at the unslotted end thereof (the inner edges of the upper jaws 5 and 6 being usually curved upwardly slightly to facilitate the entrance 10 of the cord into the pass) and the section 8 is forced to the position shown in Fig. 1 and turned about the stop-walls 10 and 11, the portion of the cord in the clamp will be gripped in three different ways, due (1) to 15 the usual clamping action of the long spring jaws adjacent to the section 8 of the cord; (2) to the increased clamping pressure exerted by the inner faces of the jaws adjacent to the slot, which faces at that side of the 20 tie-piece are usually closer together at most points than at the other side of the tie-piece because in the preferred construction shown the jaws converge somewhat from the uncut toward the cut side of the cord 25 clamp (this being clearly shown in Fig. 3); and (3) to the wedging action of those portions of the separated or cut jaws which lie in the meeting line of the jaws of the cord-clamp. In addition to this, the resistance 30 opposed to the pulling out of the cord after it is once held in place, as shown in Fig. 1, is increased very greatly because of the fact that the cord entering the clamp turns sharply about the wall or corner 11 at approximately 35 a right angle, and where it leaves the cord clamp at the wall or edge 10 is wedged in place also by being turned at a sharp angle. Any pull on the cord tending to withdraw it from the uncut side of the cord-clamp results 40 in bringing to bear upon the cord a very great amount of friction and the harder the cord is pulled the more tightly it is wedged against the wall 10 at the narrowest point of the slot 7. 45 While only one of the cord-clamps is described in detail, it will be understood that the preferred construction is one in which two similar but oppositely-disposed cord-clamps *c* and *c'* are so placed as to coact 50 properly with each other. The manner in

which the cord is held by the tie-piece or package-tie proper will be clear by referring to Fig. 1, from which it will be seen that the cord is passed once around the package and then at the point of beginning is crossed 55 and wrapped around the package at a right angle in the usual manner, after which the free end of the cord, that is, the end not engaged in a cord-clamp at the beginning of the tying operation is passed into the opposite cord-clamp and tightened up, as may be necessary in the manner shown. When the tie is finished the cord outside the tie-piece lies at approximately a right angle to the meeting line of each cord-clamp and 60 the tie-piece itself is outside the crossing point of the cord. A central hole is shown at 12 by means of which the tie-pieces may be assembled on a rod; or which may, if desired, be employed as an anchorage point 65 for a knot in those cases where a knot may be thought desirable.

What I claim is:

1. A package-tie, comprising a body portion having at one end thereof an inwardly 75 facing cord-clamp slit inwardly from one side thereof in the meeting line of the jaws to form a cord-receiving slot and the jaws of which cord-clamp converge from opposite sides of the clamp in both directions 80 substantially in said meeting line.

2. A package-tie, comprising a body portion having at opposite ends thereof a pair of inwardly facing cord-clamps slit inwardly from opposite sides respectively of 85 the body portion in the meeting lines of their jaws to form cord-receiving slots lying respectively at opposite sides of said body portion, the jaws of each cord-clamp converging from opposite sides of the clamp in 90 both directions substantially in the meeting line of the jaws of said clamp.

Signed at Ridgewood in the county of Bergen and State of New Jersey this fifth day of May A. D. 1914.

CHARLES W. DONHOLT.
